His ATTORNEY.

UNITED STATES PATENT OFFICE.

CAREY SHERWOOD, OF LOWELL, MASSACHUSETTS.

ADJUSTABLE SHAFT-HANGER.

1,221,233.

Specification of Letters Patent. Patented Apr. 3, 1917.

Application filed July 1, 1915. Serial No. 37,611.

To all whom it may concern:

Be it known that I, CAREY SHERWOOD, a citizen of the United States, residing at Lowell, in the county of Middlesex and 5 Commonwealth of Massachusetts, have invented a certain new and useful Improvement in Adjustable Shaft-Hangers, of which the following is a specification.

This invention relates to adjustable shaft 10 hangers.

The object of this invention is to permit the journal boxes to be adjusted vertically and laterally and to allow the journal boxes and their supports to be removed and 15 placed without disturbing the alinement of the shaft.

Hangers for shafting are usually supported upon wooden timbers and are liable to be shifted out of position by the shrinkage, expansion and warping of said timbers, throwing the shafting out of alinement and creating unequal pressure and friction on opposite sides of the journal boxes.

I form the hanger proper in two parts, 20 a base or foot adapted to be rigidly secured to a supporting timber substantially immovable, except for the shrinkage, expansion and warping above referred to, and an extension adjustably secured thereto by vertical bolts in such a manner that said extension may have a slight movement transversely of the shaft supported thereby and I provide means whereby said extension may be adjusted to a great exactness.

35 The extension when properly placed may be held immovable with reference to the base or foot.

The journal boxes are supported upon the same bolts which connect the extension to 40 the base and are laterally movable with said extension and are also adjustable vertically on said bolts toward or from said extension.

In the accompanying drawing, Figure 1, is a side elevation of my improved hanger, 45 the foot, extension, yoke and dripper or lower support of the journal box being partly in vertical longitudinal section; Fig. 2, a plan of said hanger with part of dripper; Fig. 3, a plan of the yoke; Fig. 4, a 50 reversed plan of the dripper; Fig. 5, represents a lock-nut, one half in elevation at the left, and at the right the other half in vertical central section.

The base or foot A is secured in place by 55 bolts, (not shown) which pass through holes

a a¹ into the supporting timbers in the usual manner, and is provided with a longitudinal groove a² of a sufficient width to receive the heads b b¹ of the screw bolts B B¹ and to allow said heads to be moved lengthwise of said base but not wide enough to allow said heads to be turned in said groove. 60

The bolts B B¹ pass vertically through longitudinal slots a⁴ a⁵ in the foot A and through holes (one of which is shown at c¹ 65 in Fig. 1) in the extension C, said extension being normally held against said foot by nuts c² c³ turning on the bolts B B¹ against the under side of said extension.

After loosening the nuts c² c³ the extension 70 and the parts supported thereby may be moved on the foot A a distance limited by the length of the slots a⁴ a⁵, transversely of the shaft D, that is, to the right or left in Fig. 1, to accommodate the journal-box E 75 laterally to said shaft.

To make such lateral adjustment with great exactness, I provide the foot or base A with two ears a⁶ a⁷ which reach down for a short distance below the top of the extension on opposite sides thereof and in these ears turn horizontal screws F F¹ which thrust against the opposite sides of said extension, the nuts c² c³ being first loosened so that by loosening either of these screws F F¹ 80 and turning the other, the extension will be moved transversely of the shaft. When the extension is so positioned that the journal-box E bears equally upon opposite sides of the shaft, the nuts c² c³ are tightened and the 85 loosened screw F or F¹ is turned against the extension to prevent any movement of said extension.

The journal-box E is or may be of usual form and is represented as supported in a 90 yoke or yoke-shaped "dripper" or drip-receiver G provided with arms g g¹, through which the bolts B B¹ pass and which rest on nuts H H¹ and check nuts h h¹ and which arms are held down on said nuts H H¹ by 95 stop-nuts H² H³ on said bolts so that when the nuts and check-nuts below said arms are unscrewed the yoke may be removed from said bolts B B¹ without disturbing the stop-nuts H² H³ or the alinement of the shaft D, 100 and said yoke may be replaced against the shaft in the same position it previously occupied and secured in place. But I have provided said yoke G with slots g⁴ g⁵ of as 105 great width as the diameter of the holes 110

commonly used for the passage of the bolts B B¹ through said arms g g¹ and integral with said holes which slots open at the sides of said arms, so that said arms may be 5 pushed laterally into place or removed therefrom without removing the nuts H H¹ h h¹ entirely from the bolts B B¹. The nuts H H¹ are lock-nuts, being each provided with a cylindrical lock h² h³ concentric with the 10 axis of said nut and the yoke G is counterbored at g⁶ g⁷ concentrically with the semi-circular closed end of the slot g⁴ g⁵ to receive and fit said lock, so that when such lock is in said counterbore the corresponding 15 arm of the yoke G cannot be moved.

The upper yoke J is held in place on the bolts B B¹ by lock-nuts H H¹ and the end portions of the arms j j¹ of said yoke J are slotted at j³ j⁴ and counterbored at j⁵ j⁶ 20 just as the lower yoke or dripper is slotted and counterbored and for the same purpose. It is evident that the upper yoke J and its nuts when held on the bolts B B¹ by said bolts passing through round holes in said 25 upper yoke cannot be removed without first removing the lower yoke C and its nuts, so

that this invention is especially desirable as applied to said upper yoke.

In the case of the lower yoke, this invention renders it unnecessary to remove the 30 nuts from the bolts with the danger of their being lost or mislaid.

This invention enables either yoke to be removed while the other yoke remains in place without disturbing the alinement of 35 the shaft.

I claim as my invention:—

The combination of a bolt, a yoke slotted to receive said bolt and having a counterbore at the inner end of said slot, and a nut 40 turning on said bolt and having a concentric, hollow cylindrical projection, to enter and fit said counterbore and to prevent a lateral movement of said yoke on said bolt in the direction of said slot.

In witness whereof, I have affixed my signature in presence of two witnesses.

CAREY SHERWOOD.
